PICTURE FRAME

Wayne K. Bessinger, Rte. 1, Box 198,
Bourbon, Ind. 46504

Filed May 25, 1973, Ser. No. 363,864

Term of patent 14 years

Int. Cl. D6—07

U.S. Cl. D6—239

Fig. 1

FIG. 1 is a front and right side perspective view of a picture frame showing my new design; and

FIG. 2 is a front elevational view.

The rear of the picture frame is substantially planar and unornamented.

I claim:

The ornamental design for a picture frame, as shown and described.
